[57] CLAIM

The ornamental design for a container for liquids, substantially as shown and described.

DESCRIPTION

FIG. 1 is a top perspective view of a container for liquids showing my new design;

FIG. 2 is a bottom perspective view showing the side and end not seen in FIG. 1;

FIG. 3 is a top plan view;

FIG. 4 is a side elevational view; and

FIG. 5 is an elevational view looking from the right of FIG. 4.
